US00D616730S

(12) **United States Design Patent**
Dennes

(10) **Patent No.:** **US D616,730 S**
(45) **Date of Patent:** **** *Jun. 1, 2010**

(54) **DETACHABLE CABLE MANAGER**

(75) Inventor: **William Wayne Dennes**, Wyoming (AU)

(73) Assignee: **ADC GmbH**, Berlin (DE)

(**) Term: **14 Years**

(21) Appl. No.: **29/280,445**

(22) Filed: **May 29, 2007**

(30) **Foreign Application Priority Data**

Nov. 30, 2006 (AU) 15503/2006

(51) **LOC (9) Cl.** **08-05**

(52) **U.S. Cl.** **D8/356**

(58) **Field of Classification Search** ..... D8/105, D8/107, 333, 349, 354, 356, 358, 367, 373, D8/382, 383, 394–396, 400; D13/155, 184; D26/76; 24/18, 197, 561; 174/68.3, 101, 174/153 G, 650, 656; 242/400.1, 405.1, 242/405.2, 600, 603; 248/65, 74.1–74.4, 248/201, 214, 215, 229.26, 302, 304, 316.7, 248/316.8; 439/131, 135, 142, 367, 369, 439/371, 472, 501, 535; 361/826

See application file for complete search history.

CLAIM

The ornamental design for the detachable cable manager, as shown and described.

DESCRIPTION

FIG. 1 is a top plan view of a detachable cable manager showing my design;

FIG. 2 is a left side elevational view thereof;

FIG. 3 is a right side elevational view thereof;

FIG. 4 is a front elevational view thereof;

FIG. 5 is a bottom plan view thereof;

FIG. 6 is a rear elevational view thereof; and,

FIG. 7 is a perspective view thereof.

The broken line in FIG. 5 is included to illustrate an unclaimed detail and forms no part of the claimed design.

1 Claim, 6 Drawing Sheets
